UNITED STATES PATENT OFFICE.

CARL ENGBERG, OF ST. JOSEPH, MICHIGAN, ASSIGNOR TO ABEL W. WELLS
AND JOHN W. MULLEN, OF SAME PLACE.

DESIGN FOR A BOX-BLANK.

SPECIFICATION forming part of Design No. 33,511, dated November 6, 1900.

Application filed October 9, 1900. Serial No. 32,552. Term of patent 14 years.

To all whom it may concern:

Be it known that I, CARL ENGBERG, a citizen of the United States, and a resident of St. Joseph, in the county of Berrien and State of Michigan, have invented and produced a new and original Design for a Box-Blank, of which the following is a full, clear, and exact description.

Reference is to be had to the accompanying drawing, forming a part of this specification, in which the figure is a plan view of a paper-box blank, showing my design.

The leading feature of the design consists in the configuration of the box-blank made the subject of the accompanying illustration.

The design in its entirety consists of a center piece A, having rounded corners B and side flanges C, extending from the sides of the center piece A and appearing at their ends with somewhat inwardly-deflected end flaps D, each flap also appearing on its outer side edge with narrow flaps E, reaching onto the

end flaps D, and the ends of the center piece A appearing with end flanges F, extending between opposite end flanges D and projecting somewhat beyond the same, as is plainly shown in the drawing.

The joints between the center piece A, the side flanges C, and the end flanges F appear as creases G, and similar creases H are the joints of the flanges C and flaps E.

Having thus fully described my invention, I claim as new and desire to secure by Letters Patent—

The design for the box-blank herein shown and described.

In testimony whereof I have signed my name to this specification in the presence of two subscribing witnesses.

CARL ENGBERG.
